(57) **CLAIM**

The ornamental design for a winch with control pack, as shown and described herein.

DESCRIPTION

FIG. 1 illustrates a perspective view of a winch with control pack;

FIG. 2 illustrates a front view of the winch with control pack as shown in FIG. 1;

FIG. 3 illustrates a rear view of the winch with control pack as shown in FIG. 1;

FIG. 4 illustrates a left side view of the winch with control pack as shown in FIG. 1;

FIG. 5 illustrates a right side view of the winch with control pack as shown in FIG. 1;

FIG. 6 illustrates a top view of the winch with control pack as shown in FIG. 1; and,

FIG. 7 illustrates a bottom view of the winch with control pack as shown in FIG. 1.

The broken lines illustrate portions of a winch with control pack that form no part of the claimed design.

1 Claim, 4 Drawing Sheets
